ALFRED HEALD, OF PHILADELPHIA, PENNSYLVANIA, ASSIGNOR TO
McCALLUM, CREASE & SLOAN, OF SAME PLACE.

DESIGN FOR CARPET.

Specification forming part of Design No. 6,714, dated June 24, 1873; application filed June 6, 1873.

To all whom it may concern:

Be it known that I, ALFRED HEALD, of the city and county of Philadelphia, State of Pennsylvania, have invented a Design for a Carpet-Pattern, (B,) of which the following is a specification:

The figure in the accompanying drawing clearly represents my design for a carpet-pattern, which consists of a series of precisely similar adjoining medallions, A, of a circular or nearly circular shape. Each of these medallions has an ornamental center piece, a, a border composed of two concentric circles, b, and the interior foliated ornamentation shown,

there being also a small diamond-shaped figure, c, at the point of junction of the medallions, and a small octagonal figure, d, in the spaces between the said medallions.

Irrespective of the colors employed, I claim—
The design for a carpet-pattern, substantially as described, and as represented in and by the accompanying drawing.

In testimony whereof I have signed my name to this specification in the presence of two subscribing witnesses.

Witnesses: ALFRED HEALD.
